Application July 18, 1958, Serial No. 749,551

Claims priority, application Czechoslovakia July 18, 1957

7 Claims. (Cl. 12—53.3)

The present invention relates generally to the manufacture of rubber boots, and more particularly is directed to an improved device for rolling the rubber strip which is laid over the rear seam of each rubber boot while the latter is carried by a conveyor.

Heretofore, the rolling of the strip laid over the rear seam of a rubber boot has been carried out with a metal roller having a cylindrical surface and which is manually pressed against the curved surface of the leg portion of the boot being produced while the roller is moved along the strip several times in both directions. The failure of the operator to maintain a uniform manual pressure of the cylindrical roller against the strip during the repeated movement of the roller along the strip frequently causes inadequate adherence of the strip to the leg portion of the boot and thereby results in an increase in the number of seconds or rejects. Further, the need to continuously apply manual pressure for urging the roller against the leg portion of the boot results in considerable muscular fatigue, frequent blistering of the worker's hands and overstraining of the wrist. Another disadvantage of the described existing procedure consists in the necessity of manually aligning and straightening the strip relative to the rear seam as the strip is laid against the rear seam of the boot, and these manual operations increase the time required for the attachment of the strip to the boot with consequent losses in the daily production output.

Accordingly, it is an object of the present invention to provide a device which automatically smooths or rolls the rear strip laid over the seam at the back of the rubber boot, and which operates in synchronism with the intermittent movement of the conveyor carrying the boots being manufactured, thereby to eliminate the manually performed operations of the above described existing procedure.

In accordance with an aspect of the invention, the device for smoothing or rolling the strip laid over the seam at the rear of each rubber boot carried by the conveyor includes a support structure extending above the conveyor transversely relative to the direction of movement of the latter and carried by an upright which is rigidly joined to the frame of the conveyor, with such support structure including guide rods carrying a movable assembly which is actuated by a fluid pressure operated device and which includes a contoured roller movable along the strip laid over the rear seam of a boot in response to operation of the fluid pressure operated device while being resiliently urged against the strip.

Further, in accordance with the invention, the operation of the fluid pressure operated device causing the movement of the contoured roller along the strip laid over the rear seam of the boot is automatically synchronized with the intermittent movement of the conveyor so that the need for intervention by the worker or operator is greatly minimized in order to achieve a substantially higher production rate as well as an improvement in the quality of the manufactured boots.

2

The above, and other objects, features and advantages of the invention, will be apparent in the following detailed description of an illustrative embodiment thereof, which is to be read in connection with the accompanying drawings forming a part hereof, and wherein:

Fig. 1 is a perspective view of the device embodying the invention;

Fig. 2 is a fragmentary perspective view of a portion of the device shown in Fig. 1; and

Fig. 3 is a further fragmentary perspective view of another portion of the device shown in Fig. 1.

Referring to the drawings in detail, and initially to Fig. 1 thereof, it will be seen that the device embodying the present invention is associated with a conveyor D carrying spaced apart metal lasts K upon which rubber boots are to be manufactured. The lasts K are arranged on the conveyor D so that, at the location of the smoothing or rolling device embodying the invention, each last K will be disposed with the leg portion of the related boot extending transversely relative to the direction of movement of the conveyor, and with the toe portion of the boot directed downwardly.

The rolling or smoothing device embodying the invention includes an upright 28 disposed at the back of the conveyor D and fixedly secured to the frame R of the conveyor. The upper end of upright 28 is formed with a longitudinally split tubular portion 47 having its axis extending transversely relative to the direction of movement of the conveyor D to receive one end of a support tube 27. The split upper end portion 47 of the upright has a clamping screw extending across the longitudinal slit thereof and rotatable by a hand wheel 34 to either loosen the portion 47 so that the tube 27 can be longitudinally adjusted with respect thereto or to clamp the portion 47 upon the end of tube 27 received therein.

It will be apparent that the tube 27 overhangs the conveyor D and, at its free end, supports a bracket 33 which is clamped about the tube 27 and includes a depending portion having a laterally widened lower part provided with spaced apart apertures slidably receiving ends of rods 16 and 16' extending parallel to the axis of tube 27. The ends of rods 16 and 16' remote from bracket 33 are fixedly connected to a head or cover 29 provided at one end of a cylinder 20 which has its axis arranged parallel to that of the tube 27, while the opposite end of cylinder 20 is provided with a mounting portion having a dovetail, or other similarly shaped groove slidably receiving a projection of corresponding cross-sectional shape depending from the tubular portion 47 at the top of upright 28 so that the cylinder 20, as well as the tube 27 can be longitudinally adjusted with respect to the upright 28. The mounting portion of cylinder 20 may be further provided with suitable set screws engageable with the part of tubular portion 47 slidably received in the groove of the cylinder in order to lock the latter in an adjusted position with respect to the upright 28.

A piston 11 is axially movable within cylinder 20 and carries sealing rings 13 which are held on the piston by collars 12 or the like so that the leakage of fluid under pressure past the piston 11 will be minimized.

A piston rod 7 extends axially from piston 11 through the cylinder head 29 and, at its free end, carries a pivot pin 14 (Fig. 3) which, at its opposite ends, is supported by sleeves 15 and 15' slidable on rods 16 and 16', respectively. Coil springs 17 are provided on the rods 16 and 16' adjacent the bracket 33 and the cylinder head 29 so that, at the opposite ends of the operation stroke of the piston 11 within cylinder 20, sleeves 15 and 15' abut against the springs 17 which thereby resiliently cushion the deceleration of piston 11 at the opposite ends of its operation stroke.

A lever 8 is provided with a forked upper end portion

32 (Figs. 1 and 3) which is pivoted on the pin 14, and the lever 8 is further formed with a longitudinally extending slot 37 opening at the opposite side faces of the lever to slidably receive bolts which extend laterally from a lever extension 31 which is arranged at one side of lever 8. The slot 37 and the bolts slidably received therein serve to maintain the extension 31 in longitudinal alignment with lever 8 during the longitudinal adjustment of the extension relative to the lever. In order to hold the lever 31 in a selected longitudinally adjusted position relative to lever 8, the upper end of extension 31 is provided with a laterally directed flange 30 which overlies the top surface of lever 8 and which is formed with a tooth 38 engageable in a selected one of a series of spaced apart notches 36 formed in the top surface of lever 8. Further, the flange 30 of extension 31 may be provided with a longitudinal slot receiving suitable bolts which can be screwed into tapped bores formed in the top surface of lever 8 intermediate the notches 36 in order to clamp the extension 31 in its adjusted position relative to lever 8.

The lower end of lever extension 31 has a bent arm 49 extending therefrom, and a smoothing roller 4, which preferably has a contoured resilient surface for accommodating itself to the shape of the boot on the last K, is rotatably journaled between bent arm 49 and the free end of lever extension 31.

Coil springs 10 and 10' are connected, at one end, to a laterally extending anchor rod 39 (Figs. 1 and 2) which is suitably secured to the flange 30 of lever extension 31 and, at their other ends, to an anchor rod 40 which extends laterally with respect to the axis of piston rod 7 and which is supported by an arm or holder 41 depending from piston rod 7 and fixedly secured on the latter. The springs 10 and 10' urge the lever 8 and its extension 31 to swing about pivot pin 14 in the direction moving roller 4 downwardly toward a boot 1 positioned on a last K which is located at the station occupied by the upright 28 while the conveyor D is at rest.

In order to maintain the roller 4 in a raised, inoperative position during the intermittent movements of the conveyor D, the device embodying the invention further includes a bent arm 35, which, at its upper end, is secured to the head 29 of cylinder 20 and, at its lower end, has a forked portion 48 rotatably carrying an abutment roller 9 positioned under and in back of the inclined lever 8. Thus, when the piston 11 is displaced within cylinder 20 in the direction toward upright 28, that is, in the direction for retracting the piston rod 7, the inclined lever 8 depending from the pivot pin 14 is moved against the abutment roller 9 which is in a fixed position relative to the cylinder 20 so that the abutment roller 9 then acts to swing the lever 8 and its extension 31 in the upward direction, against the action of the springs 10 and 10', for displacing roller 4 to the desired raised, inoperative position. On the other hand, when piston 11 is moved in the direction away from upright 28, that is in the direction extending piston rod 7 from cylinder 20, lever 8 is correspondingly bodily displaced away from abutment roller 9 so that the springs 10 and 10' are then free to draw or urge lever 8 and its extension 31, and hence also roller 4, in the downward direction.

In accordance with the invention, when the conveyor D is brought to rest with one of its lasts K carried by a carriage 3 and supporting a boot 1 located at the position of the upright 28, and a strip 2 is applied over the rear seam of the boot, fluid under pressure, which may be either compressed air or a hydraulic liquid, is supplied alternately to the opposite ends of the cylinder 20 in order to effect reciprocation of piston 11 within cylinder 20 so that roller 4 is made to roll along strip 2 with a yieldable pressure resulting from the action of the springs 10 and 10'.

In order to control the supplying of fluid under pres-

sure to cylinder 20, the device embodying the invention further includes a suitable shaped radial cam 5 fixed on a cam shaft 6 which is rotatably journaled in the frame R of the conveyor and which is driven for a predetermined number of revolutions by an electric motor (not shown) following the actuation of a push-button switch (not shown) by the operator of the device. The periphery of cam 5 is engaged by a cam follower roller 42 which is rotatably supported at the end of a pivoted lever 43. Lever 43 is pivotally connected, intermediate its ends, to a link 19 which is, in turn, pivotally connected to a control lever 44 which operates an inlet valve 18 and an outlet valve 23 provided at the upper and lower parts of a control cylinder 26 having a piston (not shown) movable therein. The upper end of control cylinder 26 is connected to the back end of cylinder 20 by a feed conduit or pipe 24 opening into cylinder 20 through a metering valve 25, while the lower end of control cylinder 26 and the forward end of cylinder 20 are interconnected by an outlet pipe or conduit 46 which is also connected to a pipe line 21 containing a supply of fluid under pressure.

When the cam shaft 6 is rotated, cam 5 rocks the lever 43 to cause corresponding rocking of the lever 44 so that the control cylinder 26 serves first to supply fluid under pressure to the back end of cylinder 20 for causing forward movement of piston rod 7, and then to supply fluid under pressure to the forward end of cylinder 20 for effecting backward movement of piston rod 7 during each revolution of the cam shaft.

30 The apparatus described above operates as follows: A boot 1 is placed upon each of the lasts K supported by a carriage 3 of the conveyor D during a period when the latter is at rest and, at the same time, the strip 2 is laid over the back seam of the boot which faces upwardly on the last.

35 During each intermittent movement of the conveyor D, the cam shaft 6 is at rest and disposed so that the cam 5 causes the control cylinder 26 to supply fluid under pressure to the forward end of cylinder 20, whereby piston rod 7 is retracted or drawn rearwardly in order to engage the pivoted lever 8 with the abutment roller 9 and thereby raise roller 4 to its inoperative position. At the end of each intermittent movement of conveyor D, a last K, with a boot 1 thereon, comes to rest at the station or location of the upright 28 so that the boot 1 then underlies the raised roller 4. The operator at such station or location then actuates the control for the motor (not shown) driving cam shaft 6 so that the latter is automatically rotated for a predetermined number of revolutions, and this rotation, as previously described, causes the supplying of fluid under pressure to cylinder 20 in a manner to effect the repeated reciprocation of piston 11 within cylinder 20. During such repeated reciprocation, the lever 8 moves bodily in the forward and rearward direction and, when disengaged from abutment roller 9, the springs 10 and 10' act resiliently upon lever 8 to urge roller 4 into rolling contact with the strip 2 applied to the back seam of the boot. Thus, roller 4 is repeatedly moved along the strip 2 in order to smooth 40 the latter against the leg portion of the boot and thereby ensure the adherence of the strip to the boot.

45 When rotation of cam shaft 6 is completed, cam 5 returns to its normal or inoperative position in which fluid under pressure is supplied to the forward end of cylinder 50 20 thereby to draw piston rod 7 in the rearward direction for again engaging lever 8 with abutment roller 9 for raising roller 4 to its inoperative position. With the roller 4 returned to its inoperative position, the conveyor D again effects an intermittent movement to bring another last K with a boot 1 thereon into position under the roller 4. When the conveyor D is again at rest, the operator once more causes rotation of the shaft 6 in order to repeat the action of the smoothing roller 4 upon the strip 2 of the boot 1 then located at the station occupied 55 by the device embodying this invention.

When additional finishing operations are performed on the successive boots at locations along the conveyor D following the station occupied by the device embodying this invention, the finished boots are stripped from the lasts so that the latter can again receive boots which are to be subjected to the smoothing action of the roller 4.

It will be apparent from the above that the device embodying the present invention serves to smooth the strip 2 laid over the back seam of each boot 1 in order to ensure the adherence of the strip to the boot, and that this operation is performed without requiring the tiresome manual procedures previously employed, as described herein. Further, the device embodying the invention serves to improve the uniformity of the smoothing of the strip 2 against the leg portion of the boot 1 and thereby improves the quality of the product, while permitting a substantial increase in the rate of production.

Although an illustrative embodiment of the invention has been described in detail herein with reference to the accompanying drawings, it is to be understood that the invention is not limited to that precise embodiment, and that various changes and modifications may be effected therein without departing from the scope or spirit of the invention, except as defined in the appended claims.

We claim:

1. A device for smoothing a connecting strip which is laid over the back seam extending along the leg portion of a rubber boot, comprising a last for supporting the boot with the leg portion of the latter extending horizontally and having its back seam along the top thereof, an upright having a support tube extending horizontally from the upper end thereof and overlying said last with the axis of said tube being generally parallel to the axis of the leg portion of the boot on said last, a pair of laterally spaced apart guide rods extending parallel to said tube below the latter, a pivot pin extending between said guide rods, means slidably mounting said pivot pin on said guide rods for movement along the latter, a longitudinally adjustable lever assembly pivoted, at one end, on said pivot pin and inclined downwardly from the latter, a pressure roller rotatably mounted at the other end of said lever assembly with the axis of said roller extending horizontally at right angles to said axis of the support tube so that said roller can roll along the connecting strip of a boot on said last in response to the movement of said pivot pin along the guide rods, an actuating cylinder having a piston reciprocable therein and a piston rod projecting axially from the cylinder, said cylinder being arranged with its axis extending parallel to the axis of said guide rods and disposed laterally intermediate the latter, said piston rod being connected to said pivot pin to displace the latter along said guide rods in response to the movement of said piston in said cylinder, and means operative to supply fluid under pressure alternately to the opposite ends of said cylinder to cause reciprocation of said piston and corresponding movement of said roller back and forth along a connecting strip laid over the back seam of a boot on said last.

5 2. A device as in claim 1; wherein said upright has a clamping portion at its upper end receiving one end of said support tube, and the latter has a bracket depending from the other end thereof, said actuating cylinder being supported, at one end, from said clamping portion of the upright and having a head at its other end; and wherein said guide rods are mounted, at their opposite ends, in said bracket depending from said tube and in said head of the actuating cylinder.

10 3. A device as in claim 2; further comprising spring means connected between said lever assembly and said piston rod to urge said lever assembly to pivot in the direction moving said pressure roller downwardly against said last.

15 4. A device as in claim 3; wherein said spring means includes a pair of helical tension springs arranged at opposite sides of said lever assembly, a lateral rod fixed to said lever assembly and having said springs anchored to its opposite ends, a bracket depending from said piston rod, and a lateral rod carried by the last mentioned bracket and having said springs anchored to its opposite ends.

20 5. A device as in claim 1; wherein said lever assembly includes two elongated parts relatively movable parallel to each other to vary the length of said lever assembly, and means releasably securing said parts to each other in a selected longitudinally adjusted position.

25 6. A device as in claim 1; further comprising an abutment member fixedly mounted in relation to said guide rods and engaged by said lever assembly as said piston nears one of its extreme positions in said cylinder to pivot said lever assembly in the direction raising said roller relative to said last.

30 7. A device as in claim 6; further comprising an intermittently moved conveyor carrying said last for movement of the latter to and away from a location under said support tube; and wherein said piston is maintained at said one extreme position during movement of said conveyor.
